UNITED STATES PATENT OFFICE.

LUCIEN A. BUTTS, OF RUSSELL, IOWA.

WIRE-FENCE TIGHTENER.

SPECIFICATION forming part of Letters Patent No. 363,314, dated May 17, 1887.

Application filed May 27, 1886. Renewed April 7, 1887. Serial No. 234,099. (No model.)

To all whom it may concern:

Be it known that I, LUCIEN A. BUTTS, a citizen of the United States of America, residing at Russell, in the county of Lucas and State of Iowa, have invented certain new and useful Improvements in Wire-Fence Tighteners; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to certain new and useful improvements in wire-fence stretchers or tighteners, the object of my improvement being to provide a cheap, convenient, and effective means for building wire fences or tightening the wires thereof.

20 My invention consists in the construction and combination of the parts, as will be herein-after fully set forth, and specifically pointed out in the claims.

25 In the accompanying drawings, which illustrate my invention, Figure 1 is a perspective view of my improvement, showing the same applied to a fence-post. Fig. 2 is a plan view, partly in section. Fig. 3 is a sectional view 30 taken through the line *x x* of Fig. 2. Fig. 4 is a perspective view of the operating-lever; and Fig. 5 is an inverted detail perspective view of a modification of my improvement.

35 A refers to the end or corner post of a wire fence, which is provided with a brace, *a*. To the vertical post the wire-stretcher is attached, said stretcher consisting, essentially, of a bed-plate, *B*, which bed-plate has attached thereto horizontally-projecting pivoted arms *C C*, the 40 ends of which are provided with inwardly-projecting hooks *c*, which are adapted to embrace the sides of the fence-post. These hooked arms are pivotally attached to the bed-plate by means of pivots *c*, which extend through the 45 rear edge of the bed-plate. The front edge, *d*, of the bed-plate has a straight edge, so as to secure a large bearing-surface upon the face of the fence-post. The pivoted arms *C*, hereinbefore described, may be bifurcated, as shown 50 in Fig. 3, so as to lie above and below the bed-plate *B*, and at the same time permit said

arms to be swung to and from each other. When the construction shown in Fig. 5 is employed, the arms *C* extend through slots formed in a downwardly-projecting portion, *C'*, at the 55 rear edge of the bed-plate *B*, said slots serving as guides, thereby dispensing with bifurcating the arms.

60 D refers to a central upwardly-projecting portion, to which a collar, *E*, is rigidly attached in any suitable manner, and through this collar passes a shaft, *F*, which has rigidly secured thereto, by means of pins *f f*, supplemental collars *G* and *G'*. These collars have inwardly-projecting portions *g*, which extend 65 within the ring *E* and abut upon a flange, *e*, which is formed integral with the shaft *F*. The collar or ring *G* is provided circumferentially with a series of projecting teeth, *h*, and the collar or ring *G'* is also provided with 70 projecting ratchet-teeth *i*, said ratchet-teeth being adapted to engage with a pawl, *I*, which is pivotally attached to one side of the portion *D*.

75 The shaft *F* is provided near each end with pins *f'*, which project through the same and form a convenient means for attaching the wire to be stretched thereto.

80 J refers to the operating-lever, which is provided with a curved end, said curved end having a projecting portion, *j*, which is adapted to engage with the teeth *h*, and adjacent thereto said lever is also provided with another projecting portion, *j'*, which also engages with said teeth. By means of this lever 85 *J* the shaft can be readily turned, so as to wind the wire thereon, and when turned will be held in place by the pawl *I*, which engages with the ratchet-teeth.

90 By means of the device hereinbefore described the wires may be wound on either side of the post, and the pivoted hook-arms will retain the same securely in position. The teeth *h*, which project from the collar *G*, are slightly inclined at their forward edges, so that the 95 projecting portions *j* and *j'* of lever *J* will secure a firm hold thereto. The device hereinbefore described is extremely simple in construction, portable, and is readily secured to or detached from a fence-post, and will hold 100 the wires when stretched while they are being secured to the post. By employing the lever

J to turn the shaft, instead of a crank-handle, a large amount of leverage can be secured, and the operator can stand facing the wire when tightening the same.

5 I claim—

1. The improved wire-fence tightener herein described, consisting of a bed-plate having hooked arms pivoted thereto, which are adapted to engage with a fence-post, a bearing for a horizontal shaft attached to said bed-plate, and a shaft provided with collars, which is located within said bearing, said collars having formed upon their peripheries projecting teeth *h* and ratchet-teeth *i*, with which a 15 pawl is adapted to engage, the parts being

organized substantially as shown, and for the purpose set forth.

2. In a wire-fence tightener, a bed-plate, B, provided with pivoted arms having hooked ends, and an upwardly-projecting bearing for 20 a shaft, in combination with the shaft F, having collars G and G', rigidly secured thereto, pins *f'*, pawl I, and operating-lever J, substantially as set forth.

In testimony whereof I affix my signature in 25 presence of two witnesses.

LUCIEN A. BUTTS.
